(57) **CLAIM**

The ornamental design for an artificial fingernail case, as shown and described.

DESCRIPTION

FIG. 1 is a perspective view of the artificial fingernail case, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a perspective view thereof; the broken line showing of the artificial fingernails is for illustrative purposes only and forms no part of the claimed design.
